UNITED STATES PATENT OFFICE.

HERMANN LEMP, OF ERIE, PENNSYLVANIA, ASSIGNOR TO GENERAL ELECTRIC COMPANY, A CORPORATION OF NEW YORK.

SYNCHRONIZING OF SHAFTS.

Application filed October 6, 1921. Serial No. 505,709.

To all whom it may concern:

Be it known that I, HERMANN LEMP, a citizen of the United States, residing at Erie, in the county of Erie, State of Pennsylvania, have invented certain new and useful Improvements in Synchronizing of Shafts, of which the following is a specification.

The present invention relates to the synchronizing of shafts and has for its object 10 to provide an improved structure and arrangement whereby a plurality of shafts driven by separate means are tied together so as to insure that they will always revolve at the same speed and in the same relative 15 directions.

For a consideration of what I believe to be novel and my invention, attention is directed to the accompanying description and the claims appended thereto. 20 One application of my invention is in connection with internal combustion engines of the opposed piston type wherein the opposed pistons drive separate shafts each shaft in turn driving a generator, and in 25 the drawing I have specifically illustrated such application. Engines of this type (utilizing two separate shafts) are particularly suited for high speed because they are easy to balance and all parts are of equal 30 weights and dimensions. It will be understood, however, that the invention is not necessarily limited thereto.

In the drawing, the figure is a diagrammatic view illustrating my invention.

Referring to the drawing, 1 and 2 are 35 shafts which are to be driven at the same speed and in the same relative direction. They drive electric generators 3 and 4 to which they are directly connected by couplings 5 and 6, the generators delivering 40 either direct or alternating current. Shafts 1 and 2 are the crank shafts of an internal combustion engine of the opposed piston type, it being understood that by the opposed 45 piston type of engine I mean any engine arrangement wherein each cylinder structure contains two pistons which move toward and away from a common combustion chamber. I have illustrated such an engine diagrammatically, 7 being the cylinders and 8 and 50 9 the pistons, the pistons 8 being connected to crank shaft 1 and the pistons 9 to crank shaft 2. The engine structure illustrated is 55 to be taken as indicating any suitable or desired type of engine having pistons which

drive two crank shafts and since the detail structure of the engine forms no part of the invention, further illustration and description are unnecessary.

Now, according to my invention the two shafts are normally synchronized by being electrically connected through preferably three slip rings or more if necessary on the respective shafts which slip rings are electrically connected to the respective generators and to each other. This ties the two shafts together electrically and insures their rotation at the same speed and of delivering their power to their generators directly. To insure synchronism when the engine shuts down with the excitation on the generators off and for starting when the generator fields are excited as motors and also to insure the correct relative directions of rotation of the two shafts when starting, the shafts are mechanically connected by means of a cross shaft having spiral gear wheels at its ends which mesh with gear wheels on the engine shafts. The cross shaft is made up of two parts coupled together by a suitable spring coupling which will allow an angular displacement of the shaft parts relatively to each other by an amount a few degrees over and below the electrical angle through which one generator may be displaced from the other in order to obtain synchronism. The coupling is, however, sufficiently strong that when the engine is shutting down the two shafts will be maintained in symmetrical 80 positions relatively to each other. The coupling shaft, however, is not expected to transmit more than one-half of the load of the engine, nor any of it continuously. It will thus be seen that the shafts are synchronized normally by the electrical connection, the mechanical connection being auxiliary thereto.

The slip rings for generators 3 and 4 are indicated at 10 and 11 and the connections at 12. In the particular instance shown it is desirable that shafts 1 and 2 rotate in opposite directions as indicated by the arrows and connections 12 are suitably crossed to bring about this result. The cross shaft comprises the two parts 13 and 14 connected by spring coupling 15 and provided with gear wheels 16 and 17 at its ends which mesh with gear wheels 18 and 19 on shafts 1 and 2. Spring coupling 15 may be of any suitable type and is illus-

trated only diagrammatically. The gear wheels may be suitable spiral gear wheels the teeth of which extend at angles to give the desired directions of rotation.

5 An arrangement as illustrated in the drawing is well adapted for electric ship propulsion, the generators being utilized to supply energy to motors driving the propellers.

10 In accordance with the provisions of the patent statutes, I have described the principle of operation of my invention together with the apparatus which I now consider to represent the best embodiment thereof, 15 but I desire to have it understood that the apparatus shown is only illustrative and that the invention may be carried out by other means.

What I claim as new and desire to secure 20 by Letters Patent of the United States, is:—

1. The combination with two shafts and generators driven thereby, of means for positively maintaining a certain synchronous relation in the rotation of the two shafts 25 comprising a multiphase electrical connection between the respective generator armatures whereby said armatures, and consequently their respective shafts, are held in step or time-phase, a supplementary mechanical connection between the shafts comprising a plurality of parts, and a spring coupling means inserted therein admitting of slight angular slip between said shafts whereby the load between them is shared 35 electrically through the multiphase connection and the friction load tending to cause slip when idling or starting and stopping is taken by said mechanical connection.

2. The combination with two shafts and 40 generators driven thereby, of means for synchronizing the shafts comprising slip rings on the shafts which are electrically connected to the generators and to each other and a mechanical connection between 45 the two shafts, said mechanical connection comprising a shaft formed of a plurality of parts connected by a spring coupling means.

3. The combination with a plurality of 50 shafts operating means therefor, and generators driven by the shafts, of means for synchronizing the shafts and insuring that they rotate in the same relative directions

comprising parallel electrical and mechanical connecting means between the shafts, 55 said electrical connecting means comprising a polyphase alternating current connection between the respective armatures of the generators whereby said shafts are locked in synchronism while the generators are 60 excited and said mechanical connecting means comprising an auxiliary shaft geared between said first named shafts, a spring coupling means inserted therein whereby the coupling force is shifted to the electrical 65 means while the generators are excited and to the mechanical means when not excited.

4. The combination with a plurality of shafts, operating means therefor, and generators driven by the shafts, of means for 70 synchronizing the shafts and insuring that they rotate in the same relative directions comprising parallel electrical and mechanical connecting means between the shafts, 75 said mechanical connecting means including yielding means which permits a relative angular displacement of the shafts greater than the electrical angle through which one generator may be displaced relatively to the other to obtain synchronism. 80

5. The combination with an internal combustion engine having opposed pistons, separate shafts driven thereby, and electric generators driven by the shafts, of means for synchronizing said shafts comprising 85 electrical and mechanical connections between the two shafts and in parallel to each other.

6. The combination with an internal combustion engine having opposed pistons, 90 separate shafts driven thereby, and electric generators driven by the shafts, of means for synchronizing said shafts comprising electrical and mechanical connections between the two shafts and in parallel to each 95 other, said electrical connections comprising slip rings on the shafts electrically connected to the generators and to each other, and said mechanical connection comprising a two part shaft geared to the first named 100 shafts and a spring coupling connecting said two parts.

In witness whereof, I have hereunto set my hand this 4th day of October, 1921.

HERMANN LEMP.
